WILLIAM GOODFELLOW, OF OAKLAND, CALIFORNIA.

CHARGE-MODIFYING METHOD AND APPARATUS FOR INTERNAL-COMBUSTION ENGINES.

Application filed May 5, 1924. Serial No. 711,080.

This invention relates to internal combustion engines, especially to such engines when used on automobiles, and it has to do with a means for modifying the gaseous fuel mixture supplied to such engines upon the suction stroke of the pistons.

The objects of my invention are to provide a method whereby a solid fuel or solid explosive fuel modifying substance may be admitted to the combustion chamber of the engine along with the usual gaseous charge, also to provide suitable apparatus to carry out the method, and also a special mixture of solid explosive material in dust form adapted for use with the apparatus.

Briefly stated the invention comprises a method of feeding an explosive dust or powder into the engine along with the usual vaporized gasoline and air mixture, and of utilizing the vibration of the engine or automobile or combination of both in order to control the proper feeding of the explosive dust.

The explosive material used is in effect a slow burning gun-powder, which I compound as follows:

Saltpetre 3 parts, sulphur 1 part, sawdust 1 part. I have also used a mixture of salt-petre 6 parts, sulphur 1 part, sawdust 1 part; so that the proportions of the explosive material are not definitely fixed. Neither are the materials used in making the mixture definitely fixed. Other explosive materials may be used. The sawdust I use is very fine dust. I call it plant dust. I have used wheat flour, also lamp-black in place of this sawdust.

Any substance which is composed of carbon or which upon the application of heat will form carbon, will do equally well. However, I should hesitate to use charcoal, the usual carbon content of gun-powder, because of the danger.

The materials are ground to a fine powder and mixed as a powder. The effect of the use of this explosive material in the combustion chambers of an internal combustion engine is:

1st. To burn out or oxidize the excess or free carbon usually found in combustion chambers.

2nd. To furnish solid fuel for the purposes of combustion. Plant dust as carbon and sulphur are fuels.

3rd. To furnish an excess of oxygen for

the purposes of combustion, that is more oxygen than can be obtained from the atmosphere, as saltpetre is in effect a magazine of oxygen in solid form.

In order to feed the material to the engine a receptacle for the powder is provided, a pipe extended therefrom to the intake manifold of the engine so that air will be drawn to the manifold through the powder, then vibratory means is provided to prevent clogging of the powder so as to insure a steady flow of same to the engine.

In the drawings accompanying this application Figure 1 shows a conventional automobile engine with my apparatus installed and connected to the intake manifold as described.

Figure 2 is an approximately full size sectional elevation of the powder container, Figure 3 the vibrating feeder removed from the container, Figure 4 the feed spring as seen in plan, and Figure 5 the air feed vibratory valve.

In further detail the engine (1) has the usual carburetor (2) with throttle (3) and intake manifold (4). The powder container is not necessarily, though is conveniently situated above the carburetor at (5) and has a pipe (6) extending to the manifold preferably before the throttle as shown, though not necessarily as it is my theory that all of the explosive dust is not burned instantaneously but is deposited on the walls of the combustion chamber and gradually consumed, for the beneficial results do not end abruptly upon stopping the powder; therefore an extra supply of explosive when main throttle is closed is of benefit rather than otherwise.

In Figures 2, 3, 4 and 5 the container (5) and its elements are shown, the vibrating feeder comprising the parts (7), (17), (9) and (10) being shown removed from the container for clarity.

The container (5) is preferably a brass shell with a fixed lower end and removable cover, and it has a brass tube (11) secured vertically along one side. This tube is slightly shorter than shell (5) and has an internal shoulder formed at (12) with a light coiled spring (13) resting upon it.

The tube being shorter than the shell forms a free passage over the top and under the lower end of the tube to the outer shell space. Aligned with the tube (11) is an outlet passageway (14) connected with the

pipe (6) to form the channel (14), (14') leading to the intake manifold of the engine, and at the upper end of the passage (14) is a conical seat (15).

5 The vibrating feeder comprises a tube (7) adapted to pass freely through the hole (16) in the shoulder in the tube and has at its upper end a weight (17) adapted to fit loosely within the tube (11) and rest upon the 10 upper end of spring (13) so that the tube (7) can freely vibrate up and down in the hole (16).

Secured within the lower end of tube (7) is a spiral spring (10) adapted to freely 15 slide in the passage (14)—(14') and with its lower end extending beyond the pipe (6) into the intake manifold of the engine, when the vibrating feeder is in position within tube (11).

20 When the feeder is in place the lower end of tube (7) rests on a small conical spiral spring (9) which in turn rests upon the conical seat (15). The upper end of the shell (5) is capped preferably with a hard leather cap (18) held in place by a threaded flange (19) and has an air inlet opening at (20). This air inlet is adapted to be covered by the valve (21) with the stem (22) extending through the opening and kept from falling 25 off by the small flange (23). The valve is adapted to vibrate on top of the cap through the vibration of the vehicle or engine and thus admit air to the shell, and the amount of freedom of the valve for vibration depends on the adjustment of the valve (21) on the threaded stem toward or from the 30 flange (23).

Within the shell container is placed a suitable quantity of the dust powder (24) alluded to, and with the vibrating feed and valve in position as described, the operation 40 is as follows: With the engine running the vibration of the car or engine will tend to shake a small portion of the powder under the lower end of the tube (11) into the conical seat (15). The vibration of the car will also shake the valve (21) from its seat and admit air through opening (20). The feeder through action of its weight (17) upon 45 the spring (13) keeps up a constant vibration and vibrates the spring (10) slightly inside of the pipe (6), while at the same time the spring (9) vibrates slightly at the point of entrance of the powder to the seat (15) so as to keep the powder from packing.

The intake suction besides drawing in the usual charge through the carburetor also draws air through passage (14)—(14'). Some of this air is drawn from inside the 50 spiral spring (10) and some from along the outside of the spring. Some air comes down inside tube (7) through top of tube (11) from inlet (20), and another path of the air is from the inlet (20) through or over the

55 powder under the lower end of the tube (11) into the upper end of passageway (14).

Mixed with this air is a certain amount of the explosive powder in dust form and which is drawn along with the gaseous fuel into the combustion chambers of the engine 60 to function as already explained.

Having thus described my invention it will be seen to effect the objects sought and while I show specific apparatus for carrying out the invention it is manifest that 75 many variations may be made without departing from the spirit of the invention, i. e. the feeding of an explosive powder to an engine together with the usual gaseous charge and of utilizing vibration and air 80 currents to effect a proper flow of the dust particles, and any such modifications are intended to be covered in my appended claims.

I claim:

1. In an internal combustion engine, 85 means for feeding a charge modifying powder to the gaseous fuel charge comprising a receptacle for the powder with a passage therefrom to the intake pipe of the engine, an air vent to the receptacle and a vibratory 90 valve associated therewith adapted to admit air to the powder.

2. In an internal combustion engine, 95 means for feeding a charge modifying powder to the gaseous fuel charge comprising a receptacle for the powder with a passage therefrom to the intake pipe of the engine and a vibratory feeding device adjacent the passage having a spring extending through 100 the passage into the pipe.

3. In an internal combustion engine, 105 means for feeding a charge modifying powder to the gaseous fuel charge comprising a receptacle for the powder with a passage therefrom to the intake pipe of the engine, and entering at a point before the throttle valve, and vibratory means associated with the receptacle adapted to feed the powder to the engine at its suction stroke.

4. The method of modifying the gaseous 110 fuel charge of an internal combustion engine which consists in introducing a dry powdered chemical into the gaseous charge in the forming thereof and before ignition, 115 said chemical being one adapted to liberate free oxygen upon the explosion of the adjacent fuel gases.

5. In an internal combustion engine, 120 means for feeding a charge modifying powder to the gaseous fuel charge comprising a receptacle for the powder with a passage therefrom to the intake pipe of the engine and a vibratory feeding device connected to the passage and responsive to the vibrations set up by the operation of the engine 125 to feed the powder thereinto.
